CLAIM

I claim the ornamental design for a skin massager, as shown and described.

DESCRIPTION

FIG. 1 is a perspective view of a first embodiment of a skin massager.

FIG. 2 is a front view of the first embodiment of the skin massager.

FIG. 3 is a rear view of the first embodiment of the skin massager.

FIG. 4 is a right side view of the first embodiment of the skin massager.

FIG. 5 is a left side view of the first embodiment of the skin massager.

FIG. 6 is a top view of the first embodiment of the skin massager.

FIG. 7 is a bottom view of the first embodiment of the skin massager.

FIG. 8 is a perspective view of a second embodiment of the skin massager.

FIG. 9 is a front view of the second embodiment of the skin massager.

FIG. 10 is a rear view of the second embodiment of the skin massager.

FIG. 11 is a right side view of the second embodiment of the skin massager.

FIG. 12 is a left side view of the second embodiment of the skin massager.

FIG. 13 is a top view of the second embodiment of the skin massager; and,

FIG. 14 is a bottom view of the second embodiment of the skin massager.

The broken lines shown in the figures are for the purposes of illustrating portions of the skin massager, which form no part of the claimed design.

1 Claim, 14 Drawing Sheets
